MULTIPLE SELECTIVE SWITCH

Henry R. Foltzer, Caracas, Venezuela

Application August 19, 1949, Serial No. 111,151
In Cuba July 5, 1949

2 Claims. (Cl. 200—46)

1

This invention relates to multiple selective switches of the kind employing as selecting elements metallic perforated or otherwise partially insulated stencils made of thin sheet metal.

One of the objects of the invention is to improve known switches of this kind permitting the use of plane metallic stencils consisting of a metallic sheet having apertures which correspond to contacts in circuits which are not to be energized. Although the stencils may be made of thin sheet metal, they will not overheat even though they are employed to close circuits through which large currents pass, as they are carried by a thick metallic perforated plate connected to the common return wire of all the circuits.

The improvements forming the object of the invention consist in providing a selective switch controlled by means of a conductive sheet stencil and in which means are provided to open all the different circuits at the same time, so as to subdivide the total intensity of the current which is being shorted, thus avoiding or reducing to a minimum the arcing or sparking during circuit breaking.

Another object of the invention is to provide a selective switch of the kind above referred to which requires but small pressure for energizing a large number of contacts and in which rigid springless fixed contacts are provided which, when the switch is in idle position, do not project above the metallic stencil-carrying-plate; while, when the stencil is in operating position, they project slightly through the perforations of said plate, whereby the stencil carried by said plate is pressed in a known manner by a flexible insulating pad backed by a rigid pressure plate first against the thick metallic perforated stencil-carrying plate and then against the "working" contacts, viz. those of the contacts which project out of the perforations of said stencil-carrying plate, in correspondence of unperforated parts of the metallic stencil, while the other contacts project through the metallic stencil. The contacts which engage the stencil are pressed by said pad which also presses the unperforated portions of the stencil against the plates, thus establishing a good conductive connection with said plate.

Another object is to provide a selective switch of the kind above referred to, in which the contact-carrying plate may be made in sections adapted to be connected together, thus rendering it possible to construct switches having a large number of contacts by connecting together

2

standard units each having a relatively small number of contacts.

Other objects and advantages of the invention will be apparent from the following description made with reference to the attached drawing, in which:

Figure 1 is an elevation with parts in section, showing a selective switch according to the invention with a stencil inserted in place, the switch being in open or circuit-breaking position.

Figure 2 shows diagrammatically and somewhat enlarged a part of the same switch in circuit-closing position.

Figure 3 shows, for the purpose of illustration only, a wiring diagram having nine independent circuits adapted to be selectively controlled by a small-9-contact switch.

Figure 4 shows a small stencil adapted for use with a selective switch such as shown in Figure 3.

In the embodiment shown in Figure 1, the selective switch consists of an insulating plate 1 fitted to a metallic frame 2 in which plate 1 has a number of contacts 3 embedded at regular intervals. The contacts comprise a body 3, a tail end 4 to which the wires leading to the circuits 5 to be energized are connected and a projecting head 3', preferably of reduced cross-section. The circuits 5 are connected in parallel with a common lead connected to one of the terminals 6, while the other terminal is connected through another common lead to a perforated conductive plate 7 having a thickness somewhat less than the height of contact heads 3' and a number of perforations that is equal to the number of said projecting contact heads 3', but of greater diameter than the latter, which thus may freely pass therethrough without touching the perforation walls.

Plate 7 is slidably mounted on uprights or bolts 9 provided with stop heads and is pushed away from insulating plate 1 by coil springs 8 encircling said bolts. Above plate 7 a pressure plate 10 is provided slidably mounted on columns 11 and carrying at its lower side, facing plate 7, a pad 12 made of rubber, felt or other yielding material. On columns 11 springs 14 are fitted between pressure plate 10 and base frame 2, so as to keep plate 10 away from plate 7, when it is in idle or open position, viz. when it is not positively pressed against the spring 8 by means to be described below. In the idle position of plate 10, in the gap between plate 10 and plate 7 a conductive sheet 13 may be inserted, which may be

perforated at desired portions, thus acting as selective switching means.

Plate 10 may be pressed towards plate 7 against the pressure of springs 14 by any suitable pressure means. In the embodiment shown, said pressure means consists of a cam disk 15 preferably shaped as an Archimedean spiral and rotatably mounted on a shaft mounted on a cross bar 18, on which shaft also a disk 21, provided with a trapezoidal notch 24, and a control handwheel 20 are mounted. Bar 18 carries in correspondence with disk 21 a stop finger 22 slidably mounted within a cylinder and pressed outwardly by a spring 22. A push rod 17 bearing with its lower end against plate 10 is slidably mounted within and at right angles to bar 18 and is provided upwardly, directly under cam 15, with a roller 16 rolling along the profile of cam 15.

The operation of the selective switch is as follows:

When the switch is in inoperative position, with the parts as shown in Figure 1, the stencil constituted by a thin perforated metal sheet 13, like that shown in Figure 4, is inserted in the gap between plate 7 and pad 12. By rotating cam 15 until the high part 25 thereof comes into contact with roller 16, the rod 17 will press plate 10 and pad 12 against stencil 13, which thus presses plate 7 towards plate 1, until contact heads 3' project slightly above plate 1 and are pressed either against the unperforated parts of stencil 13, or, through the perforations of the stencil, against pad 12, as shown in Figure 2. Due to the fact that stencil 13 is made of thin sheet metal (generally aluminium or copper of a thickness of the order of 2-3 tenths of millimeter), it is slightly bent at the point of contact with a head 3' (as the head of contact 26 indicated in Figure 2) while at the points where the heads 3' are aligned with the perforations (as is the case with the contacts 27, Fig. 2), these pass through the perforations. The unperforated parts of the stencil sheet 13 which are not in the immediate proximity of contact heads 3' that are pressed against the stencil plate (as contact 26, Fig. 2), are pressed against the perforated plate 7 which, being of substantial thickness, easily conducts very large currents, while the stencil acts as independent conductor only for very narrow circular areas about the active contacts 26, Fig. 2. Thus heating of the thin stencil sheet, is minimized, even when large currents pass through the contacts.

Fig. 3 shows how by inserting on plate 7 of a nine-contact switch a stencil like that shown in Figure 4, contact points 30 and 31 of the stencil will energize lamp groups 28, 29, contact point 33 will energize coil 32 and contact point 35 will energize motor 34. The other devices as shown in Figure 3 will remain de-energized; as their contacts are aligned with the perforations of stencil 13, Fig. 4. As shown in Figure 4, the stencils are usually provided with a tab 36 bearing useful indications, as indicated at 37.

When the circuits are to be de-energized or the stencil changed, handwheel 20 is rotated until roller 16 rolls off of high part 25 of cam 15 and then, by the action of springs 14 it snaps into the dwell of cam 15, thus permitting plate 10 with pad 12 and stencil-carrying plate 7 to snap into the position as shown in Figure 1 by the action of springs 14 and 8. As this snapping action is practically instantaneous, all contacts 3' are instantaneously brought out of contact

with the stencil, thus minimizing arching or sparking. Furthermore by this device changing of the stencils is rendered possible with the device connected to the current supply line.

In order to judge when the switch is in its full closing position, viz. with the plate 10 in its lowermost position, the slideable finger 22 pressed by a spring 23 fitted in a thimble is fastened to cross bar 18 in such a position as to snap into notch 24 of disk 21 when the switch is in full closing position. The position of bar 18 on columns 11, may be registered by means of nuts 19.

From the foregoing the advantages of the improved switch are apparent. It may be mentioned however that, due to the construction and mounting of plate 1, this may be made in sections, preferably of plastic material, having embedded therein a number of rigid contact wire sections, for instance pieces of copper wire having a diameter of about 2 millimeters. The plate sections will be usually provided with male and female parts at their borders for ensuring registering and locking of the plate sections. In this manner very large switches, designed for selectively switching many hundreds or thousands of circuits (as it is the case for large lamp panels for advertising purposes) may be made economically by employing standard units containing a limited number of contacts. The sections of contacts-carrying plate 1 may rest upon a perforated insulating board fitted to frame 2 and may be held together by any desired means.

It is also apparent that the invention may undergo numerous changes within the scope of the claims. Thus the contacts 3, 3', 4 need not be shaped as shown, but may be made of wire of any suitable section, and may be of the same diameter from end to end; the pressure means may be of any suitable kind, such as pressure screw, pneumatic or hydraulic pressure means; plate 1 may be slidably mounted on stems fitted under plate 10 and provided with abutment heads or the like; in which case the springs 8 may be less powerful than in the case as shown, or even may be eliminated.

I claim:

1. A multiple selective switch comprising an electrically non-conductive base plate, a plurality of contacts fixed in said plate, an apertured conductive plate mounted for movement parallelly towards and away from said base plate and having the apertures located so as to encircle elongated portions of said contacts without engaging same, a pressure plate mounted for movement parallelly to said apertured conductive plate and yieldably urged away from said conductive plate, a yieldable pad fitted to a face of the pressure plate and being adapted to press said apertured conductive plate towards the base plate so as to cause the elongated portions of said contacts to traverse the thickness of the conductive plate and to project slightly therethrough, a selectively apertured stencil made of a sheet of conductive material and adapted to be inserted between said conductive plate and said pad when the pressure plate is in retracted position, means for pressing said pressure plate and pad against said apertured conductive plate, means for conductively connecting individual leads to each of said contacts and, through the devices to be energized, to one of the terminals of the source of current, means for connecting a single return lead to said apertured conductive plate and to the other terminal of the source of current, and spring means maintaining the con-

ductive plate at a position wherein the surface of such conductive plate adjacent the yieldable pad is further removed from the base plate than are the ends of the elongated portions of the contact members.

2. A multiple switch according to claim 1 in which the yielding pad is fitted under the pressure plate and the conductive apertured plate is slidably mounted on guide stems provided with stop heads fitted in said base plate, and compression springs are fitted on said guide stems between said base plate and said conductive plate.
